US00D867062S

(12) **United States Design Patent** (10) **Patent No.:** **US D867,062 S**
(45) **Date of Patent:** **** Nov. 19, 2019**

(54) **LID**

(71) Applicant: **RUNWAY BLUE, LLC**, Alpine, UT (US)

(72) Inventor: **David O. Meyers**, East Layton, UT (US)

(73) Assignee: **Runway Blue, LLC**, Alpine, UT (US)

(**) Term: **15 Years**

(21) Appl. No.: **29/679,138**

(22) Filed: **Feb. 1, 2019**

Related U.S. Application Data

(62) Division of application No. 29/580,622, filed on Oct. 11, 2016, now Pat. No. Des. 842,030.

(51) **LOC (12) Cl.** **07-01**

(57) **CLAIM**

The ornamental design for a lid, as shown and described.

DESCRIPTION

FIG. 1 is a top perspective view of a first embodiment of a lid, shown in a position of use with an exemplary bottle; FIG. 2 is a top perspective view thereof, with the exemplary bottle shown removed for clarity of details; FIG. 3 is a bottom perspective view thereof; FIG. 4 is a front view thereof, the rear view being a mirror image thereof; FIG. 5 is a left side view thereof, the right side view being a mirror image thereof; FIG. 6 is a top view thereof; FIG. 7 is a bottom view thereof; FIG. 8 is a top perspective view of a second embodiment of a lid, shown in a position of use with an exemplary bottle; FIG. 9 is a top perspective view thereof, with the exemplary bottle shown removed for clarity of details; FIG. 10 is a bottom perspective view thereof; FIG. 11 is a front view thereof, the rear view being a mirror image thereof; FIG. 12 is a left side view thereof, the right side being a mirror image thereof; FIG. 13 is a top view thereof; and, FIG. 14 is a bottom view thereof. The dot-dash broken lines represent the bounds of the claimed design and form no part thereof. The evenly broken lines represent environmental subject matter of an exemplary bottle as well as parts of the article, none of which form part of the claimed design.
